UNITED STATES PATENT OFFICE.

THOMAS ALEXANDER FICK, OF PARIS, CANADA, ASSIGNOR TO JOHN LINDSAY, OF SAME PLACE.

MUCILAGE-BOTTLE.

SPECIFICATION forming part of Letters Patent No. 605,636, dated June 14, 1898.

Application filed September 18, 1897. Serial No. 652,132. (No model.) Patented in Canada June 25, 1897, No. 56,402.

To all whom it may concern:

Be it known that I, THOMAS ALEXANDER FICK, a citizen of the Dominion of Canada, residing at Paris, in the county of Brant and Province of Ontario, Canada, have invented certain new and useful Improvements in Mucilage-Bottles, (for which I have received Letters Patent in Canada, No. 56,402, dated June 25, 1897;) of which the following is a full and complete specification, such as will enable those skilled in the art to which it appertains to make and use the same.

This invention relates to bottles, and more particularly to that class thereof which is adapted to receive mucilage, paste, liquid glue, and other substances of a similar nature.

The object of the invention is to provide a receptacle of the above-described class which will be capable of retaining a substance as above enumerated and permit the use of the same without a resulting accumulation upon and about the neck of the bottle, due to its being there deposited, and the moisture contained in the preparation evaporating, leaving a hardened coagulated substance to obstruct the opening and interfere with the perfect insertion and withdrawal of the brush or other article by means of which the contents of said bottle are to be distributed.

It is also the object of my invention to provide suitable means for supporting the brush when it is detached from the bottle when not in use, which, while being simple, will prevent contact of the gum with objects in proximity to the brush.

A further object of the invention is to provide a simple and effective mode of attaching a brush to the cover which will permit a new brush to be substituted therefor when a brush shall become worn out.

A still further object is to provide a receptacle of the above-described class that will be simple in construction, efficient in operation, and comparatively inexpensive to manufacture.

The invention consists in the novel features of construction hereinafter set forth and described, and more particularly pointed out in the claims hereto appended.

Referring to the accompanying drawings,

which form a part of this specification, Figure 1 is an elevation of my improved bottle, showing all the parts in their proper relative positions; Fig. 2, a sectional elevation of the same, and Fig. 3 a view of a disk bearing the shank to which it is designed to attach the mucilage-brush.

Like letters refer to like parts throughout the several views.

In the accompanying drawings is shown a receptacle or bottle *a*, which may be of any desired configuration, the neck *a*² thereof being provided upon its inner edge with an annular flange *b*, ranging diagonally downwardly and designed to act as a scraper to remove the superfluous material from the bristles of the brush. About this receptacle I form a casing *d*, which is so attached to the same as to form an annular compartment *d*² between the outer walls of said receptacle and the inner walls of said casing. This outer casing is provided with an annular flange *f*, the sides of which are approximately parallel with the neck of the bottle *a*, but of a height which will permit the said neck to protrude slightly above the same. At the base of this flange I form an annular depression *f*², which is adapted to form a seat for the cover of the bottle or receptacle.

The cover of the receptacle comprises a hollow annular cap *g*, the lower periphery of which is equipped with a bead or abutment *g*², which so conforms in configuration with the depression *f*² as to form a practically airtight connection between the two.

Seated and secured within the upper portion of the cap *g* is a disk *h*, which may be constructed of any desired material, having firmly attached thereto or preferably made integral therewith a depending shank or stem *h*², tapered and rounded at its lower extremity to facilitate the attachment and detachment of the brush *k*, which is provided with a cylindrical portion *k*², adapted to encompass said shank or stem. The top of the cap *g* is flattened to form a base by means of which the brush may be turned upside down and maintained in this position without danger of its being overturned, with a resulting besmearing of surrounding objects. It will also be observed that the weight of the cover is suf-

ficient to counterbalance that of the bristles of the brush even when they are covered with the mucilage or other material, thus rendering it possible to lay said brush on its side
5 without danger of the same falling into contact with surrounding objects.

The operation of my improved receptacle for mucilage, glue, paste, or other similar material is as follows: The receptacle *a* is designed to receive and retain the glutinous material and the compartment *d*², surrounding said receptacle, to receive water, the vapor from which is designed to maintain such a degree of moisture within the entire structure as will prevent the hardening or coagulation of material in the receptacle *a*. When the receptacle and the compartment are respectively provided with a sufficient quantity of the material they are designed to receive, 20 the cover *g*, carrying the brush, may be placed in the relation shown in Fig. 1, thus retaining within the entire receptacle all the vapor arising from the water in the compartment. This will not only prevent the accumulation 25 of the gummy substances on the neck of the bottle and the resulting obstruction of the same, but will preserve the quality of the material within the receptacle *a*. When the brush is to be used, all superfluous mucilage, 30 paste, or liquid glue is removed by bringing the bristles of the brush in contact with the flange *b*, which, from its being ranged diagonally downwardly, will not retain the same, but will permit it to flow back into the receptacle. This construction, in connection with the protrusion of the neck of the bottle above the parallel annular flange of the outer casing, will prevent such a clogging of the space 35 between them as will interfere with the free circulation of the vapors. When it is desired to discontinue temporarily the use of the brush, it is merely necessary to stand the same upside down upon the desk or other surface, thus preventing an unintentional and annoying distribution of the contents of the bristles 40 of the brush.

If it be desirable for any purpose to apply a new brush to the bottle, it is merely necessary to remove the old brush and by inserting the shank *h*² within the hollow portion of a new brush form an attachment between said brush and said cover which will be sufficiently permanent to render the use 50 of the new brush practicable and satisfactory. The method of attaching the disk supporting the dependent shank *h*² is simple and very effective.

By the means above described I have fully attained the objects of my invention. I have produced a receptacle for mucilage, paste, liquid glue, or other analogous substances that is simple in construction, efficient in operation, and comparatively inexpensive to manufacture. The construction above described will prevent the accumulation of hardened gum about the neck of the bottle, and the consequent obstruction and clogging

of the same, and also is free from all unnecessary appendages, thus presenting a simplicity of construction, satisfactorily accomplishing all the objects of the invention. 70

It is not my intention to limit the invention to the precise construction herein shown and described, as it is obvious that there may be many variations in minor details of construction without departing from the spirit and scope of the invention. 75

The various parts of the bottle herein described may be made of any desired material, preferably, however, of aluminium, and the 80 casing may be applied to the inner receptacle in any manner which will provide a perfectly water-tight compartment between said casing and said receptacle.

Having fully described my invention, I 85 claim as new and desire to secure by Letters Patent—

1. In an improved receptacle for mucilage and like material, a hollow cap-piece having its top portion forming an interior socket or seat, and a flat disk corresponding to the top portion of said cap and coextensive in area therewith, said disk being seated and secured in the interior socket of the cap and provided with a depending shank or stem adapted to 90 carry a brush, substantially as and for the purpose set forth.

2. In an improved receptacle for mucilage and like material, a hollow cap-piece having an exterior flat and unobstructed top portion of sufficient area to form a supporting-base when the cap is inverted, and provided with an interior socket or seat, said cap-piece carrying an interiorly projecting and depending brush, sustained from a head portion fitted in 100 said interior socket or seat, whereby the cap-piece may be inverted so that its exterior flat and smooth top face is adapted to rest upon any corresponding surface and sustain the 105 projecting brush in upright position, substantially as and for the purpose set forth.

3. In an improved receptacle for mucilage and like material, a brush member comprising a flat disk top portion having a flat and unobstructed top surface without projections 110 and of sufficient area to form a supporting-base when the brush member is inverted, said cap-piece being provided with an interior socket or seat, and a stem depending from a head portion fitted in said interior socket or 115 seat of said top disk and carrying a brush, substantially as and for the purpose set forth.

4. In an improved receptacle for mucilage and like material, a brush member, comprising a flat top disk of sufficient area to form a 120 supporting-base when the brush member is inverted, said disk carrying a depending tapering stem mounted upon a head portion seated in an interior socket or seat in the top disk, in combination with a brush having a 125 cylindrical portion adapted to receive and bind upon said tapering stem, substantially as and for the purpose set forth.

5. An improved receptacle for mucilage and

like material, comprising a hollow cap-piece having an interior socket or seat in its top portion and a flat and unobstructed exterior top surface of sufficient area to form a supporting-base when the cap is inverted, and a disk corresponding to said flat top portion of the cap and of coextensive area therewith, said disk being seated and secured within the socket of the cap and provided with a depending stem carrying a brush, substantially as and for the purpose set forth.

6. An improved receptacle for mucilage and like material, comprising a hollow cap-piece having an interior socket in its top portion and a flat and unobstructed top surface of sufficient area to form a supporting-base when the cap-piece is inverted, a disk corresponding to said flat top portion of the cap and of coextensive area therewith, said disk being seated and secured in the interior socket of the cap and provided with a depending tapering stem, and a brush having a cylindrical stem or portion receiving and binding upon said tapering stem, substantially as and for the purpose set forth.

7. In an improved receptacle for mucilage and like material, a hollow cap-piece having an imperforate top wall with an exterior flat and unobstructed top surface of sufficient area to form a supporting-base when the cap is inverted, said exterior flat top surface of the hollow cap-piece having no projections or obstructions extending from or beyond the exterior surface of the flat disk forming its top wall, and a brush member interiorly carried within said hollow cap-piece and having its top portion within the plane of the flat disk forming the top wall of the cap-piece and its lower portion projecting from the latter, substantially as and for the purpose set forth.

8. An improved receptacle for mucilage and like material, comprising a body portion having a neck-flange at the base of which is formed an annular depression or seat, a cap-piece having a depending flange with an edge corresponding to and fitting said depression and provided with an interior socket in its top portion, and a disk corresponding to said top portion of the cap and coextensive in area therewith and seated and secured in said interior socket, said disk being provided with a depending stem carrying a brush, substantially as and for the purpose set forth.

9. An improved receptacle for mucilage and like material, comprising a body portion having a neck-flange at the base of which is formed an annular depression or seat, a cap-piece having a depending flange with an edge corresponding to and fitting said depression or seat and provided with an interior socket or seat at its top, the exterior top surface of said cap being flat and unobstructed and of sufficient area to form a supporting-base when the cap is inverted, a flat disk corresponding to said flat top portion of the cap and coextensive in area therewith and seated and secured in the interior socket thereof, said disk

having a depending tapering stem, and a brush having a cylindrical portion or stem receiving and binding upon said tapering stem of the disk, substantially as and for the purpose set forth.

10. An improved receptacle for mucilage and like material, comprising a body portion having a neck-flange at the base of which is formed an annular depression, a hollow cap-piece having a depending flange provided with a beaded edge fitting said depression and with an exteriorly flat and unobstructed top face, a disk corresponding to and carried in the flat top portion of the cap-piece and having a tapering stem with a rounded end, and a brush having a cylindrical portion or stem receiving said tapered and rounded stem, substantially as and for the purpose set forth.

11. An improved receptacle for mucilage and like material, comprising a receptacle, a casing inclosing the body of said receptacle and forming a water-tight compartment open at its top with respect to said inclosed receptacle, a hollow cap-piece fitting said exterior casing and having an interior socket or seat at its top, and a disk corresponding to and fitting the top portion of the cap-piece and secured in said interior seat, said disk being provided with a depending stem carrying a brush, substantially as and for the purpose set forth.

12. An improved receptacle for mucilage and like material, comprising a receptacle, a casing inclosing the body of said receptacle and forming a water-tight compartment and open at its top with respect to said inclosed receptacle, said casing having a neck-flange, a hollow cap-piece having a depending flange fitting said neck-flange and interiorly provided with a socket or seat in its top portion and having a flat and unobstructed exterior top face of sufficient area to form a supporting-base when the cap-piece is inverted, and a disk corresponding to the free top portion of the cap and coextensive in area therewith, said disk being seated and secured in the interior socket of the cap and provided with a depending stem carrying a brush, substantially as and for the purpose set forth.

13. An improved receptacle for mucilage and like material, comprising a receptacle, a casing inclosing the body of said receptacle and forming a water-tight compartment and open at its top with respect to said inclosed receptacle, said casing being provided with a neck-flange at the base of which is formed an annular depression or seat, a hollow cap-piece having a depending flange with an edge conforming to and fitting said annular depression or seat, said cap-piece being provided with an interior socket at its top portion and with a flat and unobstructed exterior face of sufficient area to form a supporting-base when the cap is inverted, and a disk corresponding to said flat top portion of the cap and coextensive in area therewith and seated and secured in said interior socket, said disk being provided with a depending stem carrying a

brush, substantially as and for the purpose set forth.

14. An improved receptacle for mucilage and like material, comprising a receptacle having a neck-flange provided with an inwardly and diagonally projecting annular flange, a casing inclosing the body of said receptacle and forming a water-tight compartment and open at its top with respect to said inclosed receptacle, said casing being provided with a neck-flange at the base of which is formed an annular depression or seat, a hollow cap-piece having a depending flange fitting the neck-flange of the casing and provided with an edge conforming to and fitting said annular depression or seat, said cap-piece being provided with an interior socket at its top portion and with a smooth and unobstructed exterior top face of sufficient area to form a supporting-base when the cap is inverted, and a disk corresponding to said flat top portion of the cap and coextensive in area therewith, said disk being seated and secured in the interior socket of the cap and provided with a tapering depending stem, and a brush having a cylindrical portion or stem receiving and binding upon said tapering stem of the disk, substantially as and for the purpose set forth.

15. An improved receptacle for mucilage and like material, comprising a receptacle having a neck-flange provided with an interiorly and diagonally projecting annular flange, a casing inclosing the body of said receptacle and forming a water-tight compartment and open at its top with respect to said inclosed receptacle, said casing being provided with a neck-flange at the base of which is formed an annular depression or seat, a hollow cap having a depending flange fitting the neck-flange of the casing and provided with an edge conforming to and fitting said annular depression or seat, said cap being

provided with an interior socket at its top portion and with a flat and unobstructed exterior top face of sufficient area to form a supporting-base when the cap is inverted, a disk corresponding to said flat top portion of the cap and coextensive in area therewith, said disk being seated and secured in the interior socket of the cap and provided with a tapering depending stem, and a brush having a cylindrical portion or stem receiving and binding upon said tapering stem of the disk, substantially as and for the purpose set forth.

16. An improved receptacle for mucilage and like material, comprising a receptacle having a neck portion provided with an interiorly and diagonally projecting annular flange, a casing inclosing said receptacle and forming a water-tight compartment, said casing being provided with a neck-flange projecting with relation to the neck-flange of the inclosed receptacle and terminating below the top plane thereof, and a cap-piece having a depending flange fitting the neck-flange of the casing and forming a closure for the flanged projecting neck portion of the receptacle, said cap-piece carrying an interiorly depending brush carried by a head portion seated in an interior socket or seat in the cap-piece and projecting within the flanged neck portion of the receptacle, substantially as and for the purpose set forth.

In testimony that I claim the foregoing as my invention I have signed my name, in presence of the subscribing witnesses, this 13th day of September, 1897.

THOMAS ALEXANDER FICK.
